[57] **CLAIM**

The ornamental design for an anti-bacterial treated telephone handset cover, as shown and described.

DESCRIPTION

FIG. 1 is a front plan view of the anti-bacterial treated telephone handset cover of the present invention;

FIG. 2 is a back plan view of the anti-bacterial treated telephone handset cover of FIG. 1;

FIG. 3 is a left side plan view of the anti-bacterial treated telephone handset cover of FIG. 1;

FIG. 4 is a right side plan view of the anti-bacterial treated telephone handset cover of FIG. 1;

FIG. 5 is a top plan view of the anti-bacterial treated telephone handset cover of FIG. 1; and,

FIG. 6 is a bottom plan view of the anti-bacterial treated telephone handset cover of FIG. 1.

The broken lines showing in FIGS. 1 through 6 are representative of backstitching.

The triangular grid surface pattern, partially shown in FIGS. 2-6 for convenience of illustration, is continuous throughout the surfaces on which it is shown in the manner depicted in FIG. 1.
